UNITED STATES PATENT OFFICE.

EDWIN L. BURTON, OF MCKINNEY, TEXAS.

COMPRESS.

SPECIFICATION forming part of Letters Patent No. 575,103, dated January 12, 1897.

Application filed December 28, 1895. Renewed November 16, 1896. Serial No. 612,386. (No model.)

To all whom it may concern:

Be it known that I, EDWIN L. BURTON, a citizen of the United States, residing at McKinney, in the county of Collin and State of Texas, have invented certain new and useful Improvements in Surgical Instruments; and I do hereby declare the following to be a full, clear, and exact description of the invention, such as will enable others skilled in the art to which it appertains to make and use the same.

My invention relates to improvements in surgical instruments, and more especially to that class of surgical instruments which are used for stopping the flow of blood during an amputation or other similar operation.

My invention will be understood by reference to the accompanying drawings, wherein the same parts are indicated by the same letters throughout the several views.

Figure 1 is a side elevation of my instrument, the needle being shown in full lines in the approximate position it will occupy when in use, and being shown in dotted lines as straight, which form it will assume when not in use. Fig. 2 is a top plan view of instrument as shown in Fig. 1. Fig. 3 is a detail plan view of the needle used with my instrument. Fig. 4 is a similar view to Fig. 1 of a slightly-modified form of instrument. Fig.

5 is a view similar to Fig. 3 of a slightly-modified form of needle, and Fig. 6 is a detail view of the gripping device for engaging and holding the end of the needle, as seen from the right in Figs. 1 and 4.

A represents the body or frame of the instrument, which is made of any suitable material, preferably of metal, and to which the needle B is pivoted, as at b. This needle is preferably made of the best steel, and is provided at its free end with a sharp fine point b' to enable the same to be easily inserted into the flesh of the limb or other part being operated upon by the surgeon. This needle is normally straight, and is bent upward at its point and clamped in the position shown in full lines in Figs. 1 and 4 after being inserted into the flesh, as will be hereinafter more fully described.

C represents the device for gripping and holding the end of the needle when in use. This gripping device is attached to the end of the body or frame A by means of a screw c or the like passing through the opening C⁰ in the said gripping device. The jaws C' C' of

this device, provided on their inner faces with 55 teeth or catches c', are adapted to be opened and closed by means of the arms C² and C³ and thus grip the point of the needle and hold the same. The arm C³ is in the form of a segmental rack, as shown in Fig. 6, and is 60 normally pressed away from the arm C² by means of a spring c³, thus tending to hold the said arms apart and the jaws C' open. A link c² is pivotally attached to the arm C² and 65 closes the end of the arm C³, and may be moved up or down thereon to release or grip the needle.

D represents a lever-arm which is pivoted at a to the body or frame of the instrument. This lever-arm is flattened and broadened at 70 its free end D' to form a better thumb-rest for depressing the lever. The said lever is provided with an opening D⁰ therethrough, which fits over a curved arm A', provided with ratchet-teeth a' on its convex side, as shown, 75 and may be moved up and down over said arm. A thumb-catch D² is pivoted, as at d', to the lever-arm D, and is adapted to engage the ratchet-teeth a' on the arm A'. This thumb-catch is normally held in engagement 80 with one of said teeth by means of the spring d², but may be disengaged by a simple pressure of the thumb, as will be obvious.

E represents a stem which is pivoted at one end, as at d, to the lever-arm D and works 85 in an opening or guideway A² in the frame A. The opposite end of this stem E is pivotally attached, as at d⁰, to the shoe or block F, which should preferably be covered or padded with some soft material to form a cushion, so 90 as to prevent the bruising of the flesh when in use.

The body A is provided with an opening A⁰ to admit the finger of the operator and thus form a grip, while the thumb presses down 95 on the plate D', hereinbefore described.

The operation of my device is as follows: The point of the needle B, which is normally straight, as shown in dotted lines in Figs. 1 and 4, is inserted into the flesh at one side of 100 the blood-vessel to be closed, and is pushed through beneath the blood-vessel until the point comes out on the opposite side. The free end of the needle is then caught between the jaws C' of the gripping device C, where 105 it is clamped and held firmly, the needle becoming slightly bent. In the meantime the cushioned block F is in its raised position.

The needle having been inserted and clamped, the operator then inserts a finger into the opening A⁰ of the frame A, and with his thumb presses down upon the thumb-plate D' on the 5 end of the lever-arm D. This pressure of the thumb will bear the lever-arm D downward, and the stem E, carrying the cushioned block F, will press the said cushioned block down upon the flesh above the blood-vessel, and by 10 closing the same will prevent the flow of blood during the operation.

A guard-cap b² (shown in dotted lines) may be provided to fit over the point of the needle when the instrument is in use and prevent 15 the accidental injury of the operator. This cap should be provided with a short chain by which it is attached to the body or frame A of the instrument, as shown in Fig. 1.

My instrument may be made, either in whole 20 or in part, of any suitable material desired, but should preferably be of metal throughout, except for the covering of the pressure-block F, which should be chamois-leather or some similar soft material.

25 The frame or body of the instrument may be made either straight or arched, as desired, and the size of the instrument may be varied to meet requirements.

30 In Fig. 5 is shown a needle having a spear-point. I may use this form of needle, if desired, and it is preferable where a great amount of pressure is necessary to close the blood-vessel, in order that the point of the needle may be more firmly held by the gripping device.

35 Many modifications of my device might be made which could be used without departing from the spirit of my invention, and I therefore do not wish to limit myself to the exact 40 details described herein.

Having thus described my invention, what I claim, and desire to secure by Letters Patent of the United States, is—

1. In a surgical instrument of the character 45 described, the combination with a body or frame, of a resilient needle hinged to one end of said frame; a pair of pivoted jaws mounted upon the opposite end of said frame for engaging and holding the pointed end of said 50 needle; a block or shoe, and means mounted on said frame for depressing said block or shoe, substantially as described.

2. In a surgical instrument of the character 55 described, the combination with a body or frame, of a resilient needle hinged to one end of said frame; a pair of toothed jaws, arms for opening and closing said jaws, and means for holding said jaws closed, mounted upon the opposite end of said frame for engaging and 60 holding the pointed end of said needle; a block or shoe, and means mounted on said frame for depressing said block or shoe, substantially as described.

3. In a surgical instrument of the character 65 described, the combination with a body or frame, of a resilient needle hinged to one end of said frame; a pair of pivoted jaws mounted

upon the opposite end of said frame for engaging and holding the pointed end of said needle; a block or shoe; a lever-arm pivoted 70 upon said frame and connected to said block for depressing the same, substantially as described.

4. In a surgical instrument of the character 75 described, the combination with a body or frame, of a resilient needle hinged to one end of said frame; a pair of toothed jaws pivoted at the opposite end of said frame for engaging and holding the pointed end of said needle; a block; a stem pivoted to said block; a lever 80 pivoted to said stem and also pivoted to said frame, for depressing said block, substantially as described.

5. In a surgical instrument of the character 85 described, the combination with a body or frame, of a resilient needle hinged to one end of said frame; a clamping device at the opposite end of said frame for engaging and holding the pointed end of said needle; a block; a stem pivoted to said block; a lever pivoted to 90 said stem and also pivoted to said frame, for depressing said block; a curved arm on said frame provided with ratchet-teeth on one side thereof, and a thumb-catch on said lever adapted to engage said ratchet-teeth and thus 95 hold said lever down, substantially as described.

6. In a surgical instrument of the character 100 described, the combination with a body or frame, of a resilient needle hinged to one end of said frame; a clamping device at the opposite end of said frame for engaging and holding the pointed end of said needle; a block; a stem pivoted to said block; a lever pivoted to 105 said stem and also pivoted to said frame, for depressing said block; a curved arm on said frame provided with ratchet-teeth on one side thereof, and a thumb-catch on said lever adapted to engage said ratchet-teeth and hold 110 said lever down; and a finger-grip in said frame, substantially as described.

7. In a surgical instrument of the character 115 described, the combination with a body or frame, of a resilient needle hinged to one end of said frame; a pair of toothed jaws, arms for opening and closing the same, and means for holding said jaws closed, mounted upon the opposite end of said frame for engaging and holding the pointed end of said needle; a block; a stem pivoted to said block and working in a guideway in said frame; a lever pivoted to said stem and also pivoted to said frame, for depressing said block; a curved arm on said frame provided with ratchet-teeth on one side thereof, working in a guideway in 125 said lever; and a thumb-catch on said lever adapted to engage said ratchet-teeth and hold said lever down, substantially as described.

In testimony whereof I affix my signature in presence of two witnesses.

EDWIN L. BURTON.
